UNITED STATES PATENT OFFICE

PRICE EUGENE PHILLIPS, OF EVANSVILLE, INDIANA

OUTBOARD MOTOR FOR BOATS

Application filed November 8, 1929. Serial No. 405,694.

The object of the present invention is to provide a light, portable, electric outboard motor having a propeller and embodying an improved mounting and construction which can be quickly and easily attached to the stern of a small boat, and operated by an electric storage battery carried by the boat, for the purpose of propelling the boat at slow speed in quiet water.

10 The invention embodies an electric motor having a novel mounting permitting the motor to be tilted only in a substantially vertical plane, means for detachably connecting the motor to the stern of a small boat, in such manner that the motor will be securely held against sidewise tilting, and an improved arrangement of frame, preferably provided with a rudder, a tube, a rigid or flexible shaft extending through the tube 15 and driven by the motor, a propeller carried by the shaft, a guard for the propeller, and means, such as a grip or handle, whereby the motor, the frame, and the shaft, propeller and other parts may be readily rocked 20 upwardly or downwardly to submerge the propeller or to elevate it clear of the surface of the water without, however, permitting side swinging of the appliance.

25 Preferably, an electric controlling switch is located on the motor, although said switch may be otherwise disposed; and, there is a reversing lever for reversing the motor.

The mounting for the motor is of an improved ball-and-socket, frictional, type, whereby the motor is held in the position to which it is tilted so that the propeller will remain submerged, if previously submerged, or, will be maintained in elevated position clear of the surface of the water, if elevated, 30 thus obviating the necessity of holding the propeller in the water or of holding it raised above the surface thereof.

In the accompanying drawings:

Figure 1 is a side elevation, showing the 40 outboard motor applied to a small boat, the latter being broken away to disclose the battery;

Fig. 2 is a part side and part sectional elevation of the appliance.

50 An electric motor 1 serves as the power

for the propeller 2 and is included in an electric circuit 3 which derives its current from a storage battery 4, a suitable electric switch 5 being included in circuit 3 for controlling motor 1.

Extending outwardly from the motor is a frame 6 which carries a fin 7 that serves as a rudder. The frame carries a guard 8 for the propeller 2, the guard preventing the propeller from becoming fouled.

Extending through the frame is a tube 9 through which the propeller shaft 10 extends, the propeller 2 being fastened on the shaft by any suitable means such as a nut 11. The shaft 10 passes through a packing nut 60 or gland 12 to prevent water from having access to the motor 1.

The frame 6 is detachably connected to the motor 1 at 13 by bolts but other means may be provided to enable the frame 6, tube 9, 65 and the propeller shaft 10 to be detached from the motor.

A handle or pistol-grip 14 which is suitably attached to the frame 6 or motor 1, serves as a means for tilting the motor, and with it, 70 the propeller, the frame, etc., upwardly or downwardly to dispose the propeller in the water or above the surface thereof.

The shaft 10 may be a rigid shaft or of the flexible type.

75 The complete outboard motor and propeller are supported, in a detachable fashion, from the boat 15 by a duplex bracket comprising the members 16, 17 having screw clamps 18, and which are connected to a common base 19, 80 through the medium of an improved mounting which permits the motor, the propeller, and the frame to be tilted only upwardly and downwardly, without possibility of laterally shifting; and whereby the appliance is held 85 in the position to which it is shifted.

The mounting for the motor comprises a pillar 20 which is provided with a ball head 21 at its upper end. A pin 22 projects upwardly from the ball head.

90 Suitably attached to the shell of motor 1 is a tubular casing 23 provided at its upper part with a slot 24 and at its lower part with a slot 25. The slots 24 and 25 respectively receive the pin 22 and the upper part of the 95 100

pillar 20, enabling the motor to be tilted upwardly and downwardly only in a substantially vertical plane.

Contained within the tubular casing 23 are friction shoes 26, 27, having concaved or cup-shaped faces which receive and bear against the ball head 21. An expansion coil spring 28 contained within the casing 23 and bearing against a removable screw plug 29 threaded into said casing, holds the shoe 26 against the ball head 21 and the said head against the shoe 27, the latter engaging the end of the casing 23. The screw plug 29 can be taken out to disconnect the parts, when desired.

15 The pillar 20 is secured in any suitable manner to the base 19.

The battery 4 is shown as concealed under the stern seat of the boat 15 but it can be otherwise located. The switch 5 is shown as provided on the motor 1 but it can be located anywhere in the circuit 3. A reversing lever 30 is provided for the purpose of reversing the direction of rotation of shaft 10. For that purpose, any suitable reversing gears may be employed within the motor, or other expedient resorted to to effectuate the purpose.

20 The purpose of the special mounting for the motor, the frame, and the propeller is to enable the operator of the boat to raise and lower the propeller to place it in the water or dispose it above the water level, it being understood that the friction of the shoes 26, 27 on the ball head is such that the parts will remain in the position to which they are tilted. However, the provision of the pin 22 and pillar 20 in connection with the slots 24, 25, permits the entire device to be shifted only upwardly and downwardly. The 25 pistol-grip 14 constitutes a convenient means for manipulating the appliance.

25 By releasing the clamps 18, the appliance can be immediately removed from its connection to the boat.

45 What I claim is:

1. In an outboard motor for boats, a mounting for the motor comprising means for the attachment thereof to a boat, a frictional ball-and-socket joint connecting said means to the motor, comprising a casing carried by the motor, a pillar having a ball head received within said casing, a pin-and-slot connection between the ball head and the casing and a frictional shoe within the casing which bears against the ball head, said pillar being supported by the means for connecting the motor to the boat.

50 2. In an outboard motor for boats, a mounting for the motor embodying means for the attachment thereof to a boat, a frictional ball-and-socket joint connecting said means to the motor, comprising a casing connected to the motor, concaved shoes contained within the casing, spring means cooperating with

the shoes, a pillar supported by the means for connecting the motor to the boat and having a ball head received within the casing and frictionally engaged by said shoes and a pin-and-slot connection between the ball head and the casing.

55 3. In an outboard motor for boats, a mounting for the motor embodying means for the attachment thereof to a boat, a frictional ball-and-socket joint connecting said means to the motor, comprising a casing secured to the motor, concaved shoes contained within the casing, spring means co-operating with the shoes, a pillar supported by the means for connecting the motor to the boat and having a ball head received within the casing and frictionally engaged by said shoes, means being provided to limit the tilting or rocking movement of the motor and its casing on the ball head to an up and down movement with adaptability to swing laterally on the ball head, a frame carried by the motor, and a propeller carried by the frame and driven by the motor, whereby the mounting for the motor permits the propeller to be submerged or raised out of the water.

60 In testimony whereof I affix my signature.

PRICE EUGENE PHILLIPS.
